APPARATUS FOR FILLING CONTAINERS

Ronald B. McKinnis, Winter Haven, Fla.

Application October 15, 1941, Serial No. 415,123

10 Claims. (Cl. 226—68)

1

My invention relates to a method and apparatus for filling containers. This case is a continuation in part of my copending cases, Serial Nos. 299,386, filed October 13, 1939, now abandoned, and 299,387, filed October 13, 1939, now abandoned.

More particularly my invention relates to the filling of containers with liquids which it is desired to maintain sterile and unoxidized. The system hereinafter to be described may be used to fill containers with sterile unoxidized juices, such as citrus fruit juices, and the juices of vegetables, though it is not exclusively of use for this purpose.

A control process is herein described that is in part automatic and in part manual. Apparatus and methods for operation of the apparatus have been devised with certain objects in view which will be apparent from the ensuing description. Among other objects the following are specifically pointed out.

An object of the invention is to devise a method of filling containers with sterile unoxidized liquid which will be automatic, at least in part.

Another object of the invention is to devise apparatus that is positive in action, simple to manufacture and easy to repair and replace.

Still another object is to furnish a system that will prevent the introduction of sterilizing liquid into the container while the juice is being pumped into the container.

Yet another object is to furnish a system that will permit a number of containers to be filled simultaneously.

The method and apparatus herein described are adapted to be used when the operator desires to fill large containers for shipping or storage, and means have been provided for automatically stopping the feeding of the desired liquid to a container when a predetermined amount has been delivered thereto.

With these and other objects in view, which may be incident to my improvements, the invention consists in the parts and combinations to be hereinafter set forth and claimed, with the understanding that the several necessary elements comprising my invention may be varied in construction, proportions and arrangements, without departing from the spirit and scope of the appended claims.

In order to make my invention more clearly understood, I have shown in the accompanying drawings means for carrying the same into practical effect without limiting the improvements in their useful applications to the particular con-

2

structions which, for the purpose of explanation, have been made the subject of illustration.

In the drawings:

Fig. 1 diagrammatically illustrates a system for filling a plurality of containers.

Fig. 2 is a diagrammatic illustration of a control system for the control of the filling operations in the system illustrated in Fig. 1.

Fig. 3 is a timing diagram of a typical filling operation.

The system is of particular use, as above stated, in storing and shipping citrus fruit juices, which may be extracted under the conditions set forth in Patent No. 2,226,513, granted December 24, 15 1940.

In order to utilize to the maximum the hot water supply, I provide variable speed pumping means so that the volume of hot sterilizing liquid delivered to any one refillable container may be balanced in accordance with the amount of hot water available.

My system comprises a series of large capacity re-usable containers 1 having valves 2 and 3. The arrangement is such that the valves 2 and 3, 25 when the containers 1 are filled with fruit juice, can be closed and the containers removed from the system for shipping or storing.

Each container is adapted to rest on a base 4 formed with a support 5 which rests on a scale beam 6 provided with a movable weight 7 for adjusting the scale to any desired weight. The scale beam is fulcrumed on a support 8. The adjustment of the weight along the length of the arm 6 enables it to be tilted when each reusable container has been filled to the desired amount. Each of the containers 1 may be flexibly connected to the piping system to be described to permit free operation of the scale.

I have shown in the drawings a source of hot water supply 9, fed by a hot water pipe 10, controlled by a valve 11. Adapted to draw hot sterilizing water from the hot water supply 9 are pipes 12, 13, and 14. Water is sucked through the pipes 12, 13 and 14 by reversible variable speed pumps 15, 16 and 17, respectively.

These pumps in the first cycle of my operation are adapted to feed hot sterilizing water through valves 18, 19 and 20, through valves 3, to the containers 1.

By causing the pumps 15, 16 and 17 to pump hot water through the lines 21, 22 and 23 and valves 3 to the containers 1, the containers 1 may be filled with hot water and sterilized. In this filling operation the valves 2 are opened, and valves 24 and headers 25 are likewise opened.

The valves 24 control the flow of the hot sterilizing liquid to a vent line 26 which feeds back at its lower end into the source 9 of hot water supply. The valves 27 in the headers 25 are closed during this filling operation. Thus all air and gas in the apparatus and lines are purged out by the hot water and the lines and apparatus are sterilized.

The next step is to fill the lines and apparatus with a sterile non-oxidizing gas displacing the water. I have shown a pipe 28 leading from the gas supply source to a gas sterilizer 29 through a valve 30. The supply may be any inert non-oxidizing gas, such as carbon dioxide or nitrogen. The gas is sterilized by a sterilizer 29 and passes to a cooling coil 31, which is shown diagrammatically in a simple coil form. From the cooling coil 31 the gas flows through a line 32, and through valves 27 which are now open, the valves 24 having been closed, through the headers 25 and valves 2 into the containers 1.

The variable speed pumps 15, 16 and 17 have been reversed and pump the sterilizing water back through lines 21, 22 and 23, and into the hot water tank 9. This hot water passes out of the tanks 1 in front of the cool sterile non-oxidizing gas.

When the tanks 1 and the lines 21, 22 and 23 have had the water removed from them, and are filled with the inert gas, the valves 18, 19 and 20 are closed. From a suitable source of supply (not shown) through a pipe 33, a sterile non-oxidized liquid, such as orange juice, is drawn, and is pumped by means of a juice pump 34 through a line 35 and a heating coil 36. Here the juice may be sterilized, if it has not been previously sterilized. From the heating coil 36 the juice is pumped through a cooling coil 37 and a line 38 into a header 39. From the header 39, through valves 40, 41 and 42, the sterile un-oxidized juice is pumped, through valves 3 into tanks 1. The valves 18, 19 and 20 are closed during this operation, as before explained.

The juice passes through header 39, valves 40, 41 and 42 and valves 3 into the containers 1 until they are filled to the desired level, at which time the scale beam will indicate that the correct weight of juice has been discharged into the tank. Valves 3 and 2 are shut and the containers 1 can be removed for storage or shipment.

I have described the construction and operation of my system in detail, but in summary it can be said that the reversible variable speed pumps 15, 16 and 17 in the sterilizing cycle pump hot water into the tanks 1 until the tanks 1 are filled, and the vent line 26 discharges hot water back into the hot water supply tank 9. Following the sterilizing cycle, there is a gassing cycle in which the system is filled with inert gas.

The next cycle is one in which the tanks are filled with juice which has been sterilized and cooled. The juice pump 33 moves the juice through the header 39, into the tanks 1, driving out through valves 2, headers 25, valves 24 and vent line 26, the sterile inert gas. Alternatively this gas can be driven out through valves 2, header 25, valve 27, pipe 32, back to the gas supply or gas storage. When the tanks have been filled to the desired amount, as indicated by the scale beams, the valves 2 and 3 are shut, and the tanks can be removed from the system.

The system I have described is flexible, and one, two or more tanks can be filled at one time by manipulation of the valves in the headers 25. Moreover the rate at which the tanks 1 can be

filled with the hot water is individually controllable through the reversible variable speed pumps 15, 16 and 17. Where only one tank, for instance, is to be filled, the speed of the pump can be greatly increased, as the operating conditions permit such accentuated rate of pumping over that which exists when a plurality of containers are to be filled.

The variable speed water pumps are designed not only to regulate the speed of admission of water, but the speed of withdrawal as well, so that the rate of withdrawal of water may be definitely correlated to the gas supply.

The system which I have shown in Fig. 1, and which has just been described, is adapted to be controlled by a control system which is illustrated diagrammatically in Fig. 2. In order to clarify the description, it is thought that the operation should be set forth so that the desired results will be apparent as the description of the control system is given.

Fig. 3 is a chart illustrating graphically the steps which are to be performed by the control system. There is a timer motor which in a given operation is shown to be on for a period of eighty minutes. This period can be shortened or lengthened depending on the operating conditions. During the time the timer motor is working, it operates to control, first, the hot water valve which is left open during the whole period of the timer motor operation. The vent valve for venting the gas already in the system at the start of the operation is shown to be on for approximately fifty minutes. During this time the water pump is operating in the direction indicated as "forward." That is to say, hot sterilizing water is being pumped into the tanks 1, and into the lines leading to the tanks, so that the tanks and the lines are sterilized. The next cycle is one in which the water pump is reversed. This sucks the hot water out of the system through the open hot water valve.

The water pump is reversed at the same time the gas valve is open. This gas valve is the one that controls the introduction of inert sterile gas into the system, such as carbon dioxide, nitrogen, a mixture of the two, or other inert gases. The gas is sucked in the container and the lines as the hot water is evacuated. This cycle may operate for thirty minutes, more or less, depending on the operating conditions. At the end of this time the hot water valve is closed, the timer motor is then stopped and the operation of the water pump in reverse is stopped. The gas valve controlling the sterile inert gas is still left open. The system is full of the inert sterile gas, the system having been, as above indicated, sterilized prior to the introduction of the sterile inert gas.

The timer motor having now stopped, there is a time space before any other operation begins. The time space can be made as long or as short as is desired, as the next cycle is manually controlled. As above stated, the gas valve is open, the juice valve is then opened by manual operation and the juice pump turned on, thus pumping juice into the system and into the juice container until the desired amount of juice has been pumped into the container.

By operation of the scale balance and of a mercury switch on the scale beam, to be later described, the juice pump is then automatically turned off. The sterile inert gas has been discharged by the juice as it filled the container. The container may now be disconnected by clos-

ing valves 2 and 3 and the container may be shipped, or stored, as desired.

To summarize the operation, the following operations are automatic. Timer motor automatically controls the opening of the hot water valve, the opening of the vent valve, the starting of the water pump to pump sterilizing water through the system, the reversal of the water pump, the opening of the gas valve and the passage of the inert sterile gas into the system. The gas valve has been opened automatically and remains open.

The opening of the juice valve and the turning on of the juice pump are manually performed operations.

The turning off of the juice pump and the closing of the juice valve are automatically controlled.

I have provided means for the operation of the system and control of the cycles just described. The system I have illustrated is one that is partly pneumatic and partly electrical. A portion of the operation is controlled automatically, while part of the operation is manually controlled.

The desired sequence of operation having just been described, the arrangement of apparatus to effect this operation will now be explained. Reference is made to Fig. 2 where I have illustrated a juice container 1 connected through a valve 2 to a vent line 26 through the valve 24 and a gas line 32 through the valve 27. The valve 3 at the bottom of the juice container is connected through the valve 18 to the water line 21 and through the valve 40 to the juice line 39.

The illustration shown in Fig. 2 only indicates one juice container, though it is apparent that the system therein depicted can be expanded to take care of any desired number of containers. The system shown is partly pneumatic and partly electrical.

The air line will be traced so that the component parts will be apparent. Air under pressure is introduced through a line 100 having therein a valve 101, thence the air passes to a water trap and filter 102 and thence to a line 103 in which is mounted a pressure gauge 104.

The line 103 joins a line 105 which has one branch 106 that leads to an air valve 107. Another branch 108 from the line 105 passes to another complementary air valve 109.

The air valve 107 controls the flow of air into a line 110 which connects to a line 111 terminating in a pneumatic switch 112. The line 110 also has a pressure gauge 113. Line 110 is connected to a diaphragm operator 114 which is adapted to open the vent valve 24. The vent valve 24 is normally constructed to remain closed except when positively kept open through the operation of the valve operator 114.

Line 110 connects to a line 115 which carries a double diaphragm operator 116 which is adapted to open the water valve 18. As with vent valve 24, the water valve 18 only remains open when held open by the pneumatic valve operator 116. Another way to state this is to say that both valves 24 and 18 are direct acting.

In line 105 is a diaphragm valve operator 117 which is also direct acting and which is adapted to open the juice valve 40.

Connected to air valve 109 is air line 118 which is in turn connected to a pneumatic switch 119, a pressure gauge 120 and a line 121.

The line 121 is connected to a line 122 which is connected to the double diaphragm valve operating mechanism 116. The arrangement is such that upon pressure being emitted to line 122

through the operation of the air valve 109, the double diaphragm valve operating mechanism 116 will also operate to hold open the water valve 18. Thus pressure in either line 115 or line 122 will hold open the direct acting water valve 18.

Connected to line 110 is a line 123 which terminates in a pneumatic relay 124 for closing the circuit for operating the water pump motor in the forward direction, as will be later described.

Connected to line 121 is a line 125 which is connected to an air operated relay 126 which is adapted to close the circuit to control the reverse operation of the water pump motor as will be later described.

Connected to line 125 is a line 127 which terminates in a pneumatic switch 128.

The switches 112, 119, 128, and the relays 124 and 126 are all adapted to operate to close circuits upon application of pressure in the line to these elements.

I have indicated generally a timer motor 129 having a timing cam 130 and a field winding 131. The field winding 131 of the timing motor 129 is in a circuit 132 connected to a source of alternating current. Current is adapted to be passed through the field winding 131, and the timing motor 129 started by means of a starter button 133 which completes the circuit through a solenoid switch 134 normally closed, as indicated in Fig. 2 and through a switch 152" closed for automatic operation.

The starter switch button 133 is pressed down and this energizes winding 131 and starts the timer motor 129 to cause the cam 130 to rotate in the direction indicated by the arrow. The high portion of the cam passes under a cam follower 135 on a pivoted arm 136. When the cam follower 135 hits the high portion of the cam 130, this operates to open the air valve 107. This lets air into the line 110, line 111 and air switch 112 to close the circuit to the field winding 131 of the timer motor 129. Therefore on release of the starter button 133, the circuit through the field winding 131 is still maintained and the starter motor will continue its operation.

Air is also admitted under pressure through the air valve 107 to the line 110 and to diaphragm valve operating mechanism 114 which opens the vent valve 24. Likewise the water valve 18 is opened through the double diaphragm valve operator 116. The pneumatic relay 124 is pushed into the down position to close a circuit to a forward operating relay to cause the current from an alternating current line 137 to operate a water pump motor 138 in a forward direction to drive the pump 15 to pump water from the hot water supply 9 through the pipe 21 to the water valve 18.

Current is supplied when the pneumatic relay 124 has closed lead 137a from line 137 through upper contacts of the relay 124, lead 237, the pole 152' of switch 152, the stop switch 155, leads 238 and 239, the closed contacts 166 of motor control relay 163, leads 240 and 241, the lower contacts of relay 124, lead 242, to the winding 162 of the "forward" control relay 161, and through lead 137b to line 137. This energizes the winding 162 and closes the contacts of the relay 161 to supply current from the line 137 through the leads 137a, 137b and 137c, then through the three righthand contacts of relay 161 and leads 138a, 138b and 138c to the motor 138 to drive it in a forward direction to pump water into the tank 1.

As the hot sterilizing water from the tank 9 is forced into the juice container through water valve 18 and valve 3, any gases, such as air, which may be in the juice container 1 are forced out through valve 2 and vent valve 24, which is opened into the vent line 26. The operation is continued as long as the cam follower 135 is on the high part of the cam 130. When the cam follower 135 leaves the high part of the cam 130, the gases, such as air, should be thoroughly purged from the container.

The next part of the operation is the part of the operation in which the hot sterilizing water is drawn from the tank and sterile inert gas is substituted therefor.

Cam follower 135 now falls to the lowest portion of the cam 130. This closes valve 107 and opens valve 109. It will be noted that the pressure in the valve operator 114 has fallen and that the direct acting vent valve 24 is closed.

At the same time the switch 112 opens and the relay 124 opens. At the same time air valve 109 is opened which closes pneumatic switch 119, thus maintaining the circuit through the field winding 131 of the timer motor 129, and thus causing the timer motor 129 to continue its operation. The water pump motor is no longer going in the forward direction but is now shifted into the reverse direction by means of pneumatic relay 126 which closes the circuit to control the reverse direction of the water pump motor 138. The current flow from line 137 is now through line 137a, by-pass line 243, upper contacts of switch 126, lead 237, pole 152, switch 152, lead 238, lead 244, closed contacts 165 of relay 161, leads 245 and 246, lower contacts of switch 126, lead 247, winding 164 of reverse control relay 163 to conductor 137b.

The current to operate the motor flows through lines 137a, 137b and 137c to leads 138a, 138c and 138b to the motor. It will be observed that the connections 138b and 138c to the line 137 have been transposed to drive the motor in a reverse direction. The water valve 18 is still open by reason of the pressure in the line 122. The reversal of the water pump motor 138 causes the water pump 15 to draw water out of the juice container 1. Simultaneously with the closing of the reverse control circuit for the water pump motor, pneumatic switch 128 has closed to close the circuit through a mercury switch 139 carried by the scale beam 6, or a solenoid switch 139', connected in parallel therewith, through a solenoid winding 140 and a source of alternating current 141.

The solenoid switch 139' is closed normally and its winding is connected in series with the mercury switch 139. If the tank 1 is full of water at the termination of the flushing cycle and the mercury switch is open due to the overbalanced scale beam 6, the current may be supplied to the winding 140 of the relay 142 through the switch 139'. As the water is withdrawn from the tank 1 and its decrease in weight again closes the switch 139, current is supplied to energize the winding of the switch 139' and cause it to open and permit the mercury switch 139 to break the circuit when the tank has become filled with juice.

The operation of the solenoid winding 140 closes a relay 142 whose upper contacts close a circuit to a solenoid 143 which opens the gas valve 27.

The pump 15 is now operating in reverse direction and is pumping water out of the juice container 1. The gas valve 27 is open, and gas

from the gas line 32 is admitted to the juice container. The cam follower 135 now assumes the position shown in Fig. 2, where it is on the intermediate portion of the cam, that is to say, the portion that is intermediate in height. When this happens, the air valve 109 is turned in the off position. This opens the reverse relay 126 and stops the water pump motor 138. It likewise opens the pneumatic switch 128. It is to be noted, however, that solenoid relay 142 is held in the up position by reason of the passage of current through a lower portion of the switch, thus completing a circuit through the solenoid winding 140 and the mercury switch 139. Thus the solenoid winding 140 is kept energized and the solenoid winding 143 is likewise kept energized, thus keeping the gas valve 27 open.

It is to be noted that the relay 142 is closed which causes the energization of a solenoid 144 connected by electrical conductors 145 through relay 142 to the line 141. This opens the circuit through the switch 134. Thus it is impossible to start the timer motor 129 at this stage of the operation, for pushing the starter button 133 will not close the circuit through the field winding 131 of the starter motor. Note also that pneumatic switches 112 and 119 are also opened so that the motor 129 no longer revolves.

Now the juice container is ready for the introduction of juice which can be manually effected at any desired time. The juice container is full of inert sterile gas which will not oxidize the juice upon its introduction into the container 1. The operation of introducing the juice into the container is effected by pressing the "on" button 146 which closes the circuit from the leads 141 through a solenoid 147 which closes the contacts of a relay 148 that energizes the control circuit 149 of the juice pump 34.

At this stage of the procedure the relay 142 is closed and upon pressing the on button 146 a circuit is completed through the winding 147 which extends from conductor 141a through the upper closed set of contacts of relay 142 through lead 248, through winding 147, conductor 249, switch 156, lead 250, off button 151, on button 146, leads 251 and 252 to conductor 141b. The energizing of the winding 147 closes the relay 148. Upon closing of the lower set of contacts 50 of relay 148 the circuit through the winding 147 is maintained independently of the on button 146. In this instance, the flow of current is from conductor 141a, lead 248, winding 147, lead 249, switch 156, lead 250, off button 151 and lead 253 through the closed lower set of contacts and thence through lead 252 to conductor 141b. Upon completion of this circuit the winding 147 will remain energized until the off button 151 is pressed breaking the circuit.

Simultaneously, upon closing of the relay 148 a circuit is completed through the upper two sets of contacts to the winding 150 of the control valve and to the control circuit 149 of the juice pump. This circuit extends from conductor 141a through lead 248 through the upper set of contacts of relay 148 through conductor 254, winding 150, lead 255, the intermediate set of contacts on relay 148, lead 252 and thence to conductor 141b. It will be noted that the circuit 149 is connected in parallel with the winding 150 and that upon energizing the winding 150 the control circuit of the pump 149 will likewise be energized.

The diaphragm air operator element 117 for the juice valve 40 operates to open the direct acting juice valve 40 through operation of a sole-

noide operated two-way control valve 150 which admits air from the line 105 to the valve operating element 117. As explained, the valve 40 is thus opened by reason of the completion of the circuit which also controls the starting of the juice pump.

The lower contacts of the relay 148 keep the circuit through the upper contacts closed by reason of the solenoid winding 147, the circuit through which is closed through an off button 151. Thus when the on button is released, the circuit through the off button holds the relay 148 in its up position until the mercury switch 139 on the scale beam is tilted sufficiently to break the circuit. This occurs when the tank 1 is filled to the requisite amount. The breaking of this circuit opens the relay 142 and the relay 148 stops the juice pump 34 and closes the juice valve 40 and closes the gas valve 27.

Communicating with the air line 127 is a pneumatic switch 156 which is electrically connected in series with the solenoid 147 of the juice relay 148 and the current supply line 141. This switch 156 is normally closed and is opened when air is admitted to it through the valve 109. Hence during the first part of the tank sterilizing cycle, the juice switch 146 is made inoperative by the open switch 128 and during the last part by the open switch 156.

Thus it will be seen that I have devised a system in which it is not possible to introduce juice into the system while sterilizing hot water is in the system, nor is it possible to introduce sterilizing hot water while juice is being introduced.

Under certain conditions, it may be necessary to sterilize the tank 1 for a longer period of time than is provided by the automatic timing mechanism 129. I therefore provide means whereby the water pump 138 may be manually operated through its control 160. A double pole, double throw, switch 152 has one pole 152' thereof connected to switch the motor control circuit 160 from the pneumatic relays 124 and 126 to a pair of push button switches 153 and 154 to manually operate the water pump motor in either a forward or reverse direction. The shift from automatic to manual operation is effected before termination of the sterilizing cycle and while cam 130 is in position to hold valve 107 open.

To insure positively that the vent, gas and water valves 24, 32 and 18 will be in a proper position for circulating the water, the second pole 152" of the switch 152 which is connected in the lead 132b in series with the current supply 132 and winding 131 of the timer motor 129 for automatic operation is shifted to manual operation. As a result, when the switch 152 is thrown for manual operation of the water pump, the timer motor is disconnected from the circuit and the cam 130 stops, thus holding valve 107, the vent and water valves open.

After switch 152 is moved to a position for manual operation upon pressing button 153 a circuit is completed through relay winding 162 as follows: Conductor 137b, relay winding 162, lead 242, button 153, leads 241 and 240, closed contacts 166 of relay 163, leads 239 and 238, stop button 155, switch arm 152' to conductor 137a, thereby completing the circuit. Upon energizing winding 162, relay 161 is closed and then motor 138 is connected to the circuit 137 in the same manner as described in connection with the automatic operation.

When the motor 138 is to be operated in the reverse direction, button 154 is moved to the closed position and this completes the circuit

through winding 164 of relay 163 as follows: Conductor 137b, winding 164, lead 247, push button 154, lead 246, lead 245, closed contacts 165 of relay 161, lead 244, lead 238, stop switch 155, switch arm 152', conductor 137a. Upon completion of this circuit the winding 164 is energized and the relay 163 is moved to a position to close its contacts, thereby completing the circuit from motor 138 to the line 137, in the manner identical to that described in connection with the automatic operation of the motor in the reverse direction.

The switches 153 and 154 operate the relays 161 and 163 in a manner similar to the automatic relays 124 and 126 to drive the motor 138 in either a forward or reverse direction. The motion of the motor in either direction may be stopped by opening the push button switch 155 which is connected in series with maintaining contacts 167 and 168 of the relays 161 and 163, respectively.

It is to be understood that, in order to prevent high vacuum in each container 1, there will ordinarily be provision to create a sufficient pressure of gas after the containers have been filled to the desired level to prevent creation of a dangerous vacuum by absorption of the gas by the juice. This may be accomplished by means of a pump 28a in a by-pass line 28b of the gas line 28. It is contemplated that gases such as nitrogen or mixtures of gases may be employed. Nitrogen is only slightly soluble and does not present as great a problem as does pure carbon dioxide.

I claim:

1. Apparatus for filling a container with a charging liquid comprising sources of a flushing liquid and the charging liquid, conduits respectively connecting said sources with the container, a pump associated with each conduit for effecting flow of liquid therethrough, a normally closed valve in each conduit, an actuator responsive to the application of fluid pressure thereto for opening the flushing valve, a second actuator for opening the charging valve, and means responsive to the pressure of fluid applied to the flushing valve actuator rendering the charging valve actuator inoperative to prevent opening of the charging valve while the flushing valve is open.

2. Apparatus for filling a container with a charging liquid comprising sources of a flushing liquid and the charging liquid, conduits respectively connecting said sources with the container, a pump associated with each conduit for effecting flow of liquid therethrough, a normally closed valve in each conduit, a pneumatic actuator for opening the flushing valve, a solenoid for opening the charging valve, an energizing circuit for the solenoid, said circuit including a normally closed, pneumatically opened switch, a source of air under pressure, conduit means connecting the air source both with the flushing valve actuator and switch for applying air pressure thereto to open simultaneously the flushing valve and energizing circuit and thereby prevent opening of the charging valve while the flushing valve is open, and control valve means in the air conduit.

3. Apparatus for filling a container with a charging liquid comprising sources of a flushing liquid and the charging liquid, conduits respectively connecting said sources with the container, a pump associated with each conduit for effecting flow of liquid therethrough, a normally closed valve in each conduit, a pneumatic actuator for opening the flushing valve, a solenoid for opening the charging valve, an energizing circuit for the solenoid, said circuit including a normally closed,

pneumatically opened switch, a source of air under pressure, conduit means connecting the air source both with the flushing valve actuator and switch for applying air pressure thereto to open simultaneously the flushing valve and switch and thereby prevent opening of the charging valve while the flushing valve is open, control valve means in the air conduit, and actuating means for the air control valve including a single rotation cam for first opening and then closing the said control valve during a cam cycle.

4. Apparatus for filling a container with a charging liquid comprising sources of a flushing liquid and the charging liquid, conduits respectively connecting said sources with the container, a pump associated with each conduit for effecting flow of liquid therethrough, a normally closed valve in each conduit, a pneumatic actuator for opening the flushing valve, a solenoid for opening the charging valve, an energizing circuit for the solenoid, said circuit including a normally closed, pneumatically opened switch, a source of air under pressure, conduit means connecting the air source both with the flushing valve actuator and switch for applying air pressure thereto to open simultaneously the flushing valve and energizing circuit and thereby prevent opening of the charging valve while the flushing valve is open, control valve means in the air conduit, actuating means for the air control valve including a single rotation cam for first opening and then closing the said control valve during a cam cycle, an electric motor for rotating the cam, and an energizing circuit for the motor, said motor circuit including a normally closed switch having electromagnetic means for opening the same, said electromagnetic means being connected in the energizing circuit for the charging valve solenoid and energized upon closing thereof to prevent opening of the flushing valve while the charging valve is open.

5. Apparatus for filling a container with a charging liquid comprising conduit means including a pump having a reversible driving motor operative in one direction to deliver a flushing fluid from a source thereof into the container to fill the same and in a reverse direction to withdraw the flushing liquid from the container back to said source, a control circuit for the motor including a forward and a reverse relay, an energizing circuit including a first switch for energizing the forward relay and a second switch for energizing the reverse relay, mechanism including a single rotation cam associated with said switches and operative to sequentially close and then open the first and then the second switch, a second conduit means including a pump having a driving motor operative to deliver the charging liquid from a source thereof into the container, an energizing circuit for the last named motor, switch means in the last named circuit, and actuating means operated by said cam to open the switch means during the cam cycle to render the last named motor inoperative during operation of the first named motor.

6. Apparatus for filling a container with a charging liquid comprising conduit means including a pump having a reversible driving motor operative in one direction to deliver a flushing fluid from a source thereof into the container to fill the same and in a reverse direction to withdraw the flushing liquid from the container back to said source, a control circuit for the motor including a forward and a reverse relay, an energizing circuit including a first switch for energiz-

ing the forward relay and a second switch for energizing the reverse relay, mechanism including a single rotation cam associated with said switches and operative to sequentially close and then open the first and then the second switch, a second conduit means including a pump having a driving motor operative to deliver the charging liquid from a source thereof into the container, an energizing circuit for the last named motor, switch means in the last named circuit, actuating means operated by said cam to open the switch means during the cam cycle to render the last named motor inoperative during operation of the first named motor, a starting switch in the last named circuit for closing the same to start the charging liquid pump, and a stop switch in the said circuit and responsive to a predetermined weight of the charging liquid in the container for breaking said circuit to stop the charging liquid pump.

7. Apparatus for filling a container with a charging liquid comprising conduit means communicating with the container and including a pump having a driving motor imparting flow to a flushing liquid to flush the tank, a second conduit means communicating with the container and including a second pump having a driving motor for introducing the starting material from a source thereof into the container, a first circuit for controlling energization of the first motor, a second circuit for controlling energization of the second motor, circuit closing means in the first circuit responsive to the application of fluid pressure thereto for closing the first circuit, and circuit breaking means in the second circuit responsive to the application of fluid pressure to said circuit closing means to break the second circuit and render the second pump inoperative while the first pump is operating.

8. Apparatus for filling a container with a charging liquid comprising conduit means communicating with the container and including a pump having a driving motor imparting flow to a flushing liquid to flush the tank, a second conduit means communicating with the container and including a second pump having a driving motor for introducing the starting material from a source thereof into the container, a first circuit for controlling energization of the first motor, a second circuit controlling energization of the second motor, pneumatic circuit closing means in the first circuit, pneumatic circuit breaking means in the second circuit, a source of air under pressure, conduit means connecting the source with both the circuit closing and circuit breaking means, valve means in said conduit means, and mechanism including a single rotation cam for operating the valve means to first open and then close the same during a cam cycle whereby the second pump will be rendered inoperative while the first pump is operating.

9. Apparatus for filling a container with a charging liquid comprising conduit means communicating with the container and including a pump having a driving motor imparting flow to a flushing liquid to flush the tank, a second conduit means communicating with the container and including a second pump having a driving motor for introducing the starting material from a source thereof into the container, a first circuit for controlling energization of the first motor, a second circuit controlling energization of the second motor, pneumatic circuit closing means in the first circuit, pneumatic circuit breaking means in the second circuit, a source

of air under pressure, conduit means connecting the source with both the circuit closing and circuit breaking means, valve means in said conduit means, mechanism including a single rotation cam for operating the valve means to first open and then close the same during a cam cycle whereby the second pump will be rendered inoperative while the first pump is operating, a motor for rotating the cam, an energizing circuit for the motor, the cam motor circuit including a series connected circuit closing and an electro-responsive circuit breaking switch actuated by energizing the second circuit to prevent starting the cam motor while the second circuit is energized.

10. In a machine for filling a container with sterile unoxidized fruit juice or the like, said container having a normally closed pneumatic vent valve, a normally closed pneumatic sterilizing valve, a normally closed solenoid gas valve and a normally closed solenoid juice valve, a source of a sterilizing liquid, a source of sterile inert gas and a source of the juice, said sources connected respectively through said sterilizing juice and gas valve with the container, and said container being connected with the atmosphere through said vent valve, a first energizing circuit for the gas valve, a second energizing circuit energized by the first circuit for the juice valve, a normally open pneumatic switch in the first circuit, a normally closed pneumatic switch and a normally open manual switch in series therewith in the second circuit, a source of compressed air, conduit means for supplying air from said source to the pneumatic valves and switches, a first valve in the conduit for controlling air supply to the vent valve and sterilizing valve, a second valve in the conduit for controlling air supply to the sterilizing valve and pneumatic switches, mechanism including a single rotation cam associated with the air valves operative to open and then close the first valve during a first portion of the cam cycle and to open and then close the second valve during the remainder of the cycle, a reversible pump associated with the sterilizing valve, mechanism responsive to the air pressure supplied from the first valve to drive

the pump in a direction to introduce sterilizing liquid into the container to purge air therefrom and responsive to air pressure supplied through the second valve for reversing the pump to withdraw the sterilizing liquid from the container and replace it with inert gas, a juice pump associated with the juice valve, mechanism energized by closing of said manual switch for operating the juice pump to introduce juice into the container to displace the gas, and circuit breaking means in said second circuit and responsive to a predetermined weight of liquid in the container to deenergize the mechanism and stop the pump.

RONALD B. MCKINNIS.
